COMBINED DESK, CAROM POOL TABLE AND RECORD PLAYER UNIT

Allen N. Eide, 2001 Winnetka Ave. N.,
Minneapolis, Minn. 55427

Filed Feb. 9, 1967, Ser. No. 5,749

Term of patent 14 years

(Cl. D33—7)

FIG. 1 is a front perspective view of a combined desk, carom pool table and record player unit, showing my design with one of the drawers in partially open position.

FIG. 2 is a top plan view of the same with top cover removed and showing interior top design;

FIG. 3 is a right hand elevation of the same; and

FIG. 4 is a rear elevational view with the desk top in place.

The essential features of my design reside in those portions shown in full lines on the drawings.

I claim:

The ornamental design for a combined desk, carom pool table and record player unit, as shown and described.
